UNITED STATES PATENT OFFICE

HENRY W. BODENDIECK, OF TAYLORVILLE, ILLINOIS, ASSIGNOR TO TIPS' TOOL COMPANY, INC., OF TAYLORVILLE, ILLINOIS, A CORPORATION OF ILLINOIS

DISCONNECTING SWITCH

Application filed October 12, 1928. Serial No. 312,107.

This invention relates to disconnecting switches and it is an object of the invention to provide a device of this kind wherein is employed a blade together with means associated therewith for effectively locking said blade in closed position and which also operates with equal facility in effecting a release or disconnecting of the blade.

Furthermore, an object of the invention is to provide a switch of this kind wherein the means for locking the blade into closed adjustment also provides a further means for maintaining a positive connection between the contacts comprised in the switch and which is of especial importance in the event the conventional spring clip or terminal with which the blade engages becomes ineffective as a result of burning or from any other cause.

Another object of the invention is to provide a switch of this kind wherein a locking means is provided for the blade when in closed adjustment and which means also operates to facilitate the release or disconnecting of a blade, said means normally only being effective when the blade is in contact with the terminal of the contact with which the blade is adapted to have releasable engagement so that the liability of fusing of such means incident to the closing or opening of the blade is substantially eliminated.

The invention consists in the details of construction and in the combination and arrangement of the several parts of my improved disconnecting switch whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view in side elevation with a portion broken away of a disconnecting switch constructed in accordance with an embodiment of my invention, the blade being locked in closed position;

Figure 2 is a view similar to Figure 1 showing

the blade released and initially moved toward open position, a coacting hot stick being diagrammatically indicated by broken lines;

Figure 3 is a view similar to Figure 2 but showing the blade in its initially closed position and just before the locking means becomes operative, the coacting hot stick being also diagrammatically indicated by broken lines.

As disclosed in the accompanying drawing, B denotes an elongated base constructed in a conventional manner and which has engaged therewith at desired points spaced longitudinally thereof the insulators A and A'. The insulators A and A' are provided respectively with the terminal posts 1 and 1', each of which being provided with an outstanding projection or lug 2 which constitutes a terminal connection for a desired conductor. As the manner of engaging a conductor with each of these projections or lugs 2 forms no particular part of the present invention a detailed disclosure thereof is believed to be unnecessary.

Pivotedly connected, as at 3, with the terminal post 1 associated with the insulator A is the switch blade 4 of a length to have requisite engagement with and between the conventional spring clip terminals 5 carried by the terminal post 1'. The foregoing construction is well known.

The terminal post 1' inwardly of the clip terminals 5 is provided with an inwardly disposed elongated lug or plate 6 preferably integral with the terminal post 1' and the outer or free end portion of said lug or plate 6 is provided therethrough with an opening 7, the major portion of the wall of said opening being threaded. The end portion of this opening 7 opposed to the blade 4 is enlarged as at 8, for a purpose to be hereinafter more particularly referred to.

Carried by a side face of the blade 4 and in electrical connection therewith is a sleeve or barrel 9. This sleeve or barrel 9 is disposed transversely across the blade 4 and preferably with its axis at right angles to the longitudinal axis of the blade 4.

Freely disposed through this sleeve or barrel 9 is a shank 10 and at opposite sides of

the blade 4 this shank 10 is provided with the shoulders 11 and 11', said shoulders being spaced apart a distance greater than the length of the sleeve or barrel 9 whereby the shank 10 is permitted to have limited independent endwise movement through said sleeve or barrel 9.

The shoulder 11 is at the same side of the blade 4 as the lug or plate 6 and the portion 10' of the shank 10 extending beyond the shoulder 11' is threaded for engagement within the opening 7 in order to permit locking engagement of the shank 10 with said lug or plate 6 to effectively maintain the blade 4 in closed position.

The opposite or outer end portion of the shank 10 is provided with an angular head 12 adapted to be received within a socket 14 carried by an end portion of a hot stick 15, as diagrammatically indicated by broken lines in Figure 3.

In closing the switch, the hot stick is conveniently forced against the blade 4 to bring the same into requisite initial contact with the clip terminals 5 and preferably until the outer extremity of the portion 10' of the shank 10 enters within the opening 7, during which time the shoulder 11 is in contact with the adjacent end of the sleeve or barrel 9 and, of course, the shoulder 11' is slightly spaced therefrom.

The outer extremity of the portion 10' of the shank 10 is pointed, as at 16, to provide a pilot coating with the enlarged portion 8 of the opening 7 to facilitate the entrance of the portion 10' of the shank 10 within said opening 7.

The socket 14 of the hot stick 15 is then engaged with the head 12 and the shank 10 rotated to thread the portion 10' thereof into the opening 7, thus moving the blade 4 into more effective engagement with the terminals 5 and at the same time effectively locking the blade 4 in desired closed position. This locking action is highly desirable especially in view of the fact that it also serves to provide a positive connection between the blade 4 and the terminal post 1' so that in the event the clip terminals 5 should become ineffective as a result of arcing or any other cause, the blade 4 will be prevented from moving into open position and the requisite flow of current will be maintained by the connection afforded through the instrumentality of the locking means. In other words, it is to be understood that this locking means affords what may be termed a "secondary positive connection" between the blade 4 and the terminal post 1' and which secondary connection is of vital importance in connection with the maintenance of hot or high tensioned switches or kindred electrical equipment.

It is to be noted that the portion 10' of the shank 10 is permitted in the first instance to thread within the opening 7 without impart-

ing movement to the blade 4 as the shoulder 11' of the shank 10, owing to the endwise movement of the shank 10 independently of the blade 4, will not contact with said blade 4 until after the portion 10' of the shank has effective threaded engagement within the opening 7 and thus eliminating arcing between the portion 10' and the lug or plate 6.

When it is desired to open or disconnect the switch, the hot stick 15 through its socket 14 is engaged with the head 12 to unthread the portion 10' of the shank 10 from the lug or plate 6 and during such operation the shoulder 11 will have contact with the adjacent end of the sleeve or barrel 9 and thereby impart positive initial movement to the blade 4 to assure breaking of any weld which may occur as a result of arcing at the contact of the blade 4 with the terminals 5. When the portion 10' is free of the plate 6 the hook 17, diagrammatically indicated by broken lines in Figure 3, carried by the end portion of the hot stick 15 remote from the socket 14 is engaged with the blade 4 to pull the same free from the terminals 5.

From the foregoing description it is thought to be obvious that a disconnecting switch constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a switch blade and an associated terminal, a sleeve carried by the blade, a member freely insertible through the sleeve, said member being provided with shoulders spaced apart a distance greater than the length of the sleeve, said sleeve being positioned between said shoulders, an end portion of the member being threaded, the terminal having an opening with which said threaded portion of the member is engageable.

2. In combination with a switch blade and an associated terminal, a sleeve carried by the blade, a member freely insertible through the sleeve, said member being provided with shoulders spaced apart a distance greater than the length of the sleeve, said sleeve being positioned between said shoulders, an end portion of the member being threaded, the terminal having an opening with which said threaded portion of the member is engageable, said member being free of the terminal until after the switch proper is in engagement therewith, a shoulder of the

member further contacting with the blade to further engage the blade with the terminal after the member has been initially threaded within the opening.

3. In combination with a switch blade and an associated terminal, a sleeve carried by the blade, a member freely insertible through the sleeve, said member being provided with shoulders spaced apart a distance greater than the length of the sleeve, said sleeve being positioned between said shoulders, an end portion of the member being threaded, the terminal having an opening with which said threaded portion of the member is engageable, said member being free of the terminal until after the switch proper is in engagement therewith, a shoulder of the member further contacting with the blade to further engage the blade with the terminal after the member has been initially threaded within the opening, the second shoulder of the member engaging the blade when said member is unthreaded from the opening to initially impart opening movement to the blade.

4. In combination with a switch blade and an associated terminal, a sleeve carried by the blade, a member freely insertible through the sleeve, said member being provided with shoulders spaced apart a distance greater than the length of the sleeve, said sleeve being positioned between said shoulders, an end portion of the member being threaded, the terminal having an opening with which said threaded portion of the member is engageable, said member being free of the terminal until after the switch proper is in engagement therewith, a shoulder of the member further contacting with the blade to further engage the blade with the terminal after the member has been initially threaded within the opening, the second shoulder of the member engaging the blade when said member is unthreaded from the opening to initially impart opening movement to the blade, the independent endwise movement of the member assuring said member being entirely free of the terminal during the opening movement of the blade before the blade is entirely free of the terminal.

In testimony whereof I hereunto affix my signature.

HENRY W. BODENDIECK.
